No 990.

E. A. Tuttle & T. Barry

Design for Pillar or Column Base.

Patented Feb 23 1858.

Fig. 1.

Fig. 2.

Dec. 990

Edward A. Tuttle, and Thomas Barry, of New York, N.Y.
Letters Patent No. 990 - Dated Feb. 23, 1858.

The schedule referred to in these Letters Patent and making part of the same.

To all whom it may concern:

Be it known, that we E. A. Tuttle and Thomas Barry, of the city, county and state of New York, have invented a new Ornamental Design, for the Pillar of a Compass Stand; and we do hereby declare that the following is a full, clear, and exact description of the same, reference being had to the accompanying drawings making part of this specification, in which

Fig. 1. is an elevation of a compass-stand, having its pillar of my design

Fig. 2. is a horizontal section of the pillar in the line x.
x. of Fig. 1. Similar letters of reference indicate corresponding parts in both Figs.

A. A. A. represents the pillar which constitutes my design, as distinguished from the base B., and cup C. neither of which I claim. The pillar is composed of three dolphins, so disposed with their backs outwards that their heads arranged at equal distances apart and turned outwards and their pectoral fins a. a. form a broad foot to the pillar, and that their bellies and pectoral fins unite to give strength to the pillar and that their tails unite again, and their caudal fins b. b. without being united, combine to form a convex receptacle for the cup C. or for the compass box itself.

The configuration beyond what is above described, can be better understood by reference to the drawings, than by description.

G.M.P. What we claim as our invention, and desire to secure by Letters Patent, is: The design of the Pillar A.A.A. as herein described and represented in the accompanying drawings.

W. Tusch
W. Hanff
